UNITED STATES PATENT OFFICE.

PATRICK WALL, OF ALLEGHENY, PENNSYLVANIA.

OIL-CAN.

SPECIFICATION forming part of Letters Patent No. 231,634, dated August 24, 1880.

Application filed June 23, 1880. (No model.)

To all whom it may concern:

Be it known that I, PATRICK WALL, of Allegheny, in the county of Allegheny and State of Pennsylvania, have invented a new and useful Improvement in Oil-Cans; and I do hereby declare that the following is a full and exact description thereof, reference being had to the accompanying drawings, and to the letters of reference marked thereon.

10 My invention relates to an improvement in oil-cans; and it consists of constructing it of sheet-iron, brazing the joints and providing them with protecting-rings, the upper end of said can forming the section of a sphere, the 15 outer edge of which is curved so as to project beyond the cylindrical portion of the body, and the bottom flanged and placed within the lower end of the cylindrical part of the body, so that the lower edge of the cylindrical part will project below the flange of the bottom and leave 20 a single thickness of metal, which is turned outward for the purpose of holding the protecting rings in position on the cylindrical part of the can, the said upper end of the can having on 25 its inner wall a tubular and circular conduit for air, the inlet and outlet of which are near the same point, and so disposed with relation to each other and the body of the can that the oil will not flow through said conduit while 30 manipulating the can in using it in the operation of oiling machinery.

To enable others skilled in the art with which my invention is most nearly connected to make and use it, I will proceed to describe its construction and operation.

35 In the accompanying drawings, which form part of my specification, Figure 1 is a side elevation of my improvement in oil-cans. Fig. 2 is a vertical section of the same. Fig. 3 is a 40 perspective view of the protecting-rings and handle, showing the latter coupled to the former. Fig. 4 is an inverted view of the top, showing the arrangement of the air-conduit.

In the accompanying drawings, A represents the body of the can, B its top, C its bottom, and D its oil-conveying tube, all of which are constructed of sheet-iron and with 45 brazed joints. The top forms a section of a hollow sphere, the edge of which is curved inward against the outer walls of the body A, forming a curved projection at e, against which

the upper edge of the protecting-ring f rests. The bottom C is provided with a flange, g, and is inserted in the body A, so that the walls of the body project below said flange, which 55 projecting portion of the wall is turned outward and over the lower edge of the protecting-ring h, as shown at i in Fig. 2.

The protecting-rings f h are coupled to the handle J, as shown in Figs. 2 and 3, and are 60 placed upon the body A at the points of the can which are usually injured by indentations made while manipulating the can in the operation of oiling, particularly while oiling machinery in motion. The protecting-rings f h are 65 constructed, by preference, of semi-oval iron, and are held in position on the body A by means of the curved projection e of the top B, handle J, and the outward overlapping of the walls of the body at i.

70 The oil-tube D is furnished with screw-threads K, which fit into screw-threads in the top B, which part of the top is made thick by brazing a piece on its inner wall, forming sufficient thickness for forming screw-threads therein. On the 75 under side of the top is secured an air-conduit, s, which has an air-inlet at l with an outlet at m.

The oil-conveying tube D is detached from the top B for supplying the can with oil. In manipulating the can in the operation of oiling machinery the flow of the oil through the oil-conveying tube D is arrested by the operator placing his thumb over the air-inlet l.

The advantage of the oil-can herein described will be apparent to operators of machinery 85 in motion.

Having thus described my improvement, what I claim is—

An oil-can constructed of sheet-iron with 90 brazed joints, the upper and lower end of the cylindrical portion of the body surrounded with detachable protecting-rings, the upper end of said can forming a section of a hollow sphere, on the inner wall of which is arranged a circular conduit with air inlet and outlet 95 near the same point, substantially as herein described, and for the purpose set forth.

PATRICK WALL.
